No. 699,536.

Patented May 6, 1902.

H. A. KNOX.

Brake.

(Application filed Dec. 21, 1901.)

(No Model.)

UNITED STATES PATENT OFFICE.

HARRY A. KNOX, OF SPRINGFIELD, MASSACHUSETTS.

BRAKE.

SPECIFICATION forming part of Letters Patent No. 699,536, dated May 6, 1902.

Application filed December 21, 1901. Serial No. 86,787. (No model.)

To all whom it may concern:

Be it known that I, HARRY A. KNOX, a citizen of the United States of America, residing at Springfield, in the county of Hampden and 5 State of Massachusetts, have invented new and useful Improvements in Brakes, of which the following is a specification.

This invention relates to vehicle-brakes, the object of the invention being to provide a 10 brake mechanism which is equally effective whether the vehicle is going in one direction or another and one in which the movable member can be applied directly on the driving-axle of a self-propelled vehicle and the stationary expandible member directly on the 15 frame of the vehicle and adapted to be connected with actuating mechanism supported on the vehicle-body.

In the drawings forming part of this application, Figure 1 is a side elevation of a part of a self-propelled vehicle having my improved brake applied thereto. Fig. 2 is a sectional view taken on line 2 2, Fig. 1, looking in the direction of the arrow, certain parts of 25 the device beyond the section-line being broken away substantially on line 2^a. Fig. 3 is a perspective view of the brake-operating arm.

Referring to the drawings, *a* indicates a portion 30 of the side of a self-propelled vehicle; *b*, the driving-axle thereof; *c*, a counter-shaft or the crank-shaft of a motor from which movement is transmitted to the driving-axle by a suitable chain running over the sprockets *d* and *e* or other suitable driving connection. The axle *b* is shown only in the conventional manner as a driving-axle. The springs *f*, of 35 which there are two extending lengthwise of the vehicle under each side and from end to end thereof, constitute also the reaches of the running-gear frame, said frame comprising the said springs and a front and rear axle. The manner of connection between said 40 springs and said axles forms no part of the present invention, but is the subject of another application for Letters Patent of the United States filed jointly by me and one James H. Jones on November 21, 1901, under 45 Serial No. 83,118.

It is sufficient for the purposes of this application to state that that end of the spring *f* which is shown in Fig. 1 of the drawings

is provided with a cylindrically-shaped extremity *g*, which is capable of an endwise-sliding and a rotatory movement within certain 55 limits in a sleeve *h*, which is located on a bearing *i*, through which the driving-axle *b* passes and in which said axle rotates freely, said sleeve and axle being located at right angles one to another.

As shown in Fig. 2, a sprocket-wheel *e* is secured to the driving-axle in proximity to the bearing *i* and rotates therewith. This wheel is formed upon the periphery of a cup-shaped body, and aside from its capacity as 65 a driving-sprocket for the axle *b* it also serves as one of the members of the brake, for it is against the inner surface of the peripheral wall of this cup-shaped body that an expandible brake member is forced to check the 70 speed of the vehicle, all in the manner to be described farther on.

The shaft *c* is hung in a suitable hanger *k*, secured in any way to the bottom of the vehicle-body *a*, and from this hanger or this 75 shaft *c* there extends a rigid arm *l* back to the driving-axle, whereby a fixed distance between this axle and the shaft *c* is maintained. This rigid arm *l* is preferably pivotally connected with both the bearing *i* and the hanger 80 *k* and is made in two parts united by a right and left hand threaded sleeve *m*, whereby its length may be adjusted. By connecting the bearing *i* to the arm or chain-strut *l* it is evident that the sleeve *h*, through which the end 85 of the spring passes, will be maintained in a substantially horizontal position, with very little tendency to a rocking motion on the axle, and therefore the end of the spring *f* may play freely therein endwise and any 90 rotatory tendency of the bearing would be overcome by the long bearing of the end of the spring in said sleeve and the connection with the strut *l*.

The stationary expandible member of this 95 brake mechanism is preferably made of cast-iron in the form of a split ring, as shown in Fig. 1, and that part of said ring by which it is attached to the bearing *i* is provided with a solid segment-shaped web *n*, cast integral 100 therewith, and there is an arm *o*, which extends outwardly therefrom across the bearing *i*, to which it is bolted. This web, in order to stiffen this fixed end of the ring *j*, ex-

ends over substantially one-quarter of the periphery of said ring from a point close to the surface of the hub of the sprocket-wheel, as shown in dotted lines in Fig. 1 and in section in Fig. 2. The opposite end of the ring *j* has cast thereon an enlargement *p* of such dimension as will permit the formation of a slot therein, in which is located a nut *q*, which receives one end of a right and left hand threaded stud *r*. (Shown in perspective in Fig. 3.) A similar nut enters a similar slot in the portion *n* of said ring, and both nuts are grooved to hold them in position in said slots. The two ends of the ring are separated sufficiently to permit the arm *s* to be clamped to the stud *r*.

It is quite obvious that by swinging the arm *s* back and forth the free end of the ring *j* will be forced away from the end thereof, which is bolted to the bearing, and as this ring is located in the cup-shaped body of the sprocket-wheel said ring may thereby be expanded against the interior surface of the peripheral wall of said body.

25 The arm *s* is provided with a connecting-bar *t*, which extends to and is pivotally connected with the lower end of a brake-lever *u*, pivoted at *v* on the under side of the frame *a*, the opposite end of said lever extending upward 30 to a point within convenient reach of the person who is operating the vehicle.

When the brake is applied, the thrust comes directly against the bearing as a point of resistance, the tendency being to give the bearing a rotative movement around the axle *b*. This thrust is resisted by the rigidity of the strut *l* and also by the long bearing which the end of the spring has in the sleeve *h*. The parts have therefore ample strength to 40 resist the strain.

The brake, of course, is equally operative in going either forward or backward, and its construction permits its application close up to the side of the bearing *i*, whereby the opposing strains are concentrated to the greatest 45 possible degree.

While the preferred manner of constructing the split ring is that hereinbefore described, a slight modification thereof may be made, which consists in locating the web *n* 50 midway between the two ends of the split ring instead of at one end thereof, whereby the action of the arm *s* to rotate the screw-stud *r* will tend to separate both ends of the ring instead of forcing one end away from 55 the other. In other words, it would provide two movable ends instead of one. I do not, however, regard that construction as desirable when the ring is made of such diameter as would be used for ordinary road-vehicles. 60

Having thus described my invention, what I claim, and desire to secure by Letters Patent of the United States, is—

A rotatable axle, a cup-shaped body secured thereon, a bearing for said axle, a split ring 65 in said body for frictional contact with the inner surface of the peripheral wall of said body, one end of said ring having a solid web forming part thereof, whereby it is made practically rigid, an arm between said web and 70 said bearing for supporting said ring; a screw-threaded stud between the ends of said ring, and means for rotating said stud to force the free end of said ring away from said rigid end thereof to bring the ring into frictional 75 contact with the peripheral wall of said body.

HARRY A. KNOX.
